UNITED STATES PATENT OFFICE.

LOUIS FORR, OF JERSEY CITY, NEW JERSEY.

INSULATOR AND SUPPORT THEREFOR.

1,240,830.

Specification of Letters Patent. Patented Sept. 18, 1917.

Application filed February 12, 1912. Serial No. 877,936.

To all whom it may concern:

Be it known that I, Louis Forr, a citizen of the United States, and a resident of Jersey City, in the county of Hudson and State 5 of New Jersey, have invented certain new and useful Improvements in Insulators and Supports Therefor, of which the following is a full, clear, and exact description, whereby any one skilled in the art may make and 10 use the same.

The invention relates to insulators and particularly to a combined insulator and support adapted for holding and insulating an electrical conductor.

15 The object of the invention is to provide a simple and effective device for supporting and insulating conductors.

A further object is to provide a device which will not only support the conductor 20 but will thoroughly insulate even under conditions of great moisture.

A still further object is to provide a separable insulating member which may be utilized with a separable bracket member, giving 25 great facility for applying and adjusting the device to the conductor.

Referring to the drawings:

Figure 1 is an illustrative view showing the device applied to a pole and holding 30 the conductor for an arc lamp.

Fig. 2 is a view of the bracket and insulator in side elevation.

Fig. 3 is a front face view of the device shown in Fig. 2, looking from the right of 35 said figure.

Fig. 4 is a face view of one of the insulating members.

Fig. 5 is a cross sectional view of the insulator, showing the grooves and beads.

40 In many instances, it is desirable to firmly hold a conductor in a definite position and it is also necessary to so hold said conductor that it will be thoroughly insulated from the support which sustains it.

45 It is one of the objects of the present invention to provide an insulator which will thoroughly insulate the conductor even under extreme conditions of moisture and which may be readily applied to the conductor.

50 As illustrated in Fig. 1, the device is shown in conjunction with the leading wires which extend from the line wires to a lamp and are held against the side of a pole or like support.

The device consists essentially of a hold-

ing and insulating member 1, and a bracket member 2. The bracket member is preferably formed with a base-piece 3, provided with suitable perforations 4, 5, through 60 which may be extended lag screws or other devices for holding said base to a pole, wall or like support. Extending from said base is an arm 6, which may be of any desired length. This arm has a semicircular portion 7, which, in conjunction with a similarly formed clamping member 8, forms a seat within which may be clamped the insulator 1, as by the medium of bolts and nuts 9, 10.

70 The enlarged or circular portions of the bracket member and co-operating clamping member are preferably cut away as at 11, not only to lighten the structure, but to reduce the metal surface surrounding the porcelain or other conducting material 1. The bracket or holder is preferably formed of a non-corrosive metal, such as galvanized malleable iron, while the insulator 1 is preferably formed of brown glazed porcelain 80 which is very vitreous.

75 The insulating member 1 is formed in two sections 12, 13, which sections, when in place, form an insulator having a cone-shaped water-shedding top 14, provided with an annular groove 15, within which rest the bracket of the clamping member and at the lower end is provided with a skirt 16. The semicircular opening 17, is formed in each of the halves and as illustrated in Fig. 4 is serrated 90 as at 18, so that as the two halves are clamped about the insulation of the conductor, these serrations become embedded in said insulating material and prevent moisture which would tend to run down the insulator working between the conductor and the interior surface of the insulator. In order to increase the surface insulation between the bracket members and the conductor, an annular groove 19, and an annular bead 20 are arranged upon the face of each half of the insulator and extend lengthwise thereof between the central serrated opening and the holding groove 15.

100 These grooves and beads being arranged upon both sections of the insulator form an interlock to prevent displacement of the insulating sections and also provide a greater insulating surface at the line of partition of the two sections. It is obvious from the 110 above description that the two insulating sections may be readily applied to the con-

ductor on opposite sides and when bound by the bracket and clamp members 7 and 8, they will securely hold the conductor in definite position with reference to the supporting pole, wall or the like to which the bracket 6, is secured. The serrating of the central clamp opening of the insulator is important as above defined, as it prevents moisture at the inner side of the insulator and between it and the conductor. Likewise, the grooves and beads are important giving an added insulating function. These devices permit the use of a split insulator which is even more effective than a solid insulator would be.

Obviously, the exact details of the device might be varied to a considerable extent without departing from the spirit or intent of the invention which contemplates a clamping bracket readily adjustable to the insulator and the split insulator with its features of added insulation due to its constructional form.

What I claim as my invention and desire to secure by Letters Patent is:

1. In a device of the character described, a bracket member and a clamping member co-operating therewith and secured to the bracket member on opposite sides of an insulator, a two-part insulator of the petticoat type having a conical head and a dependent skirt and a central annular portion engaged by the bracket and clamp to prevent longitudinal movement of the insulator, a central opening formed in part in each section of the insulator and serrated to en-

gage and be impressed in the insulation of a wire to be held, interlocking beads and grooves arranged upon the meeting faces of the two parts of the insulating members and separated from the central opening and the bracket member by the intermediate flat meeting faces of the two parts of the insulator whereby the insulator parts may be firmly embedded with respect to the contained wire upon a clamping action of the clamp with reference to its supporting bracket.

2. In a device of the character described, a two-part insulator of the petticoat type having a conical head and a dependent skirt and a central opening formed in part in each section of the two-part insulator, serrations formed in the central opening of the insulator adapted to be embedded in the insulation of a wire to be clamped, upon compression exerted by a clamping member, a bracket forming one part of a clamping member and a clamping member co-operating therewith and adapted to compress the two parts of the insulator against the wire and interlocking grooves and beads upon the meeting faces of the two-part insulator adapted to be brought into registering engagement by the clamp and increasing the insulating surface at the partition face of the insulating sections substantially as described.
